UNITED STATES PATENT OFFICE.

SILAS H. CATE, OF WATERTOWN, MASSACHUSETTS.

DESIGN FOR ARM-HOLDER FOR CLOTHES-DRIERS.

Specification forming part of Design No. 7,360, dated April 7, 1874; application filed February 6, 1874.
 [Term of Patent 3½ years.]

To all whom it may concern:

Be it known that I, SILAS H. CATE, of Watertown, in the county of Middlesex and State of Massachusetts, have invented a Design for the Arm-Holders of Clothes-Driers, of which the following is a specification:

The nature of my design is fully represented in the accompanying photographic illustration, to which reference is made.

A represents the body or back by which the holder is attached to the wall, being chamfered at each end, as shown at *m m*. From this body a series of wide smooth circular arm supports or disks, *a a a a a*, project laterally, the upper and lower disks being whole, or constructed with but small central openings to admit the rod *z*, the middle disks or supports being provided with the larger openings *k k*.

Attached to the upper end of the rod *z*, and resting on the disk *n*, there is an acorn-shaped knob, *c*.

The distinctive feature of my design is found in the series of large annular disks attached to the back or body, and mounted with an acorn-shaped knob.

What I claim as new, and desire to secure by Letters Patent, is—

The design for an arm-holder for clothes-driers, above described, consisting of the annular disks arranged as described, and surmounted by an acorn-shaped knob, as shown.

SILAS H. CATE.
